DISPLAY DEVICE FOR MERCHANDISE

Walter Schnewind, Detroit, Mich.

Application February 21, 1949, Serial No. 77,491

5 Claims. (Cl. 312—178)

1

My improvement pertains particularly to devices made in the form of a cabinet which contains a number of panels or boards in a vertical position, the panels being spaced from each other in a parallel relation to each other. The device includes means whereby selected panels normally positioned rearwardly from the front of the cabinet may be brought forwardly and aligned side by side in one plane. More specifically, my device includes a cabinet provided with a sliding board analogous to a drawer and having said panels mounted on said board but permitting the panels to be shifted laterally with respect to said board and kept in place on side boards which are hinged to the first-mentioned board. These and other details will now be described with respect to the accompanying drawings in which:

Figure 1 is a perspective view of my device with all the panels disposed within said cabinet;

Figure 2 is a perspective view of the cabinet with a slide board drawn outwardly and with a plurality of panels mounted thereon;

Figure 3 is a perspective view of the same elements, but also with side boards set up for operative combination with the board;

Figure 4 is a perspective view of my cabinet, the view disclosing also the panels as aligned in one place for display of merchandise;

Figure 5 is a plan view of the device as shown in Figure 4;

Figure 6 is a sectional view taken on line 6—6 of Figure 5;

Figure 7 is a sectional view taken on line 7—7 of Figure 5;

Figure 8 is a sectional view taken on line 8—8 of Figure 2;

Figure 9 is a sectional view taken on line 9—9 of Figure 8;

Figure 10 is a sectional view taken on line 10—10 of Figure 3;

Figure 11 is a sectional view taken on line 11—11 of Figure 10;

Similar numerals refer to similar parts throughout the several views.

The cabinet, generally indicated by numeral 10, may be made of wood or metal or any other suitable material in the more or less conventional form in which filing cabinets are made. The cabinet, best shown in Figure 1, includes a sliding board 11, provided at the front with a face member 12 and a handle 13. Mounted on the surface of said board are a plurality of tracks 14, these being disposed transversely to the length of the board as best shown in Figure 8. The tracks are made of substantially U-shaped rails

2

marked 15, said rails having outwardly turning flanges 17, the flanges of one rail being spaced from the flanges of the adjoining rail so that a narrow slot is formed in between, leading to a laterally expanded space under the flanges. Mounted for a slideable movement within said slots are upright panels 18, each panel having a base or a foot portion 19, said foot portion fitting under the flanges 17 of two adjoining rails 15. The front surface of each panel carries a plurality of items of merchandise such as pipes 20, which are selected for illustration of the manner of use of said panels. Hinged to the sides of said board 11, which hereinafter will be called center board, are two side boards. One 21 is hinged to said central by hinges 22; the other side board 23 is hinged by means of hinges 24. The manner of the hinging is best shown in Fig. 7. Normally, the side boards are positioned under the center board 11, being aligned parallel thereto, and kept from dropping down by means of a pivoted metal finger 31, best shown in Figure 8. In Figure 7 the position of the side boards under the center board is indicated by numerals 21a and 23a respectively. When spread out, the side boards extend at the same plane as said center board 11, said side boards being kept so by means of arms 25 pivotally attached to the underside of board 11 by means of bolts 26.

Each side board is provided with two parallel slots 27 spaced from each other and running lengthwise with respect to said side board. Disposed transversely upon said side board is a single track 28 made of two parallel rails 29 mounted upon two T-blocks 30, one such block being slidably disposed in each slot 27. The rails have the same spacing between them as said rails 15 on center board 11, described above, and they afford sufficient space between them for reception of base members 19 of the individual panels 18. It will be understood that said track 28, supported by blocks 30, may be moved longitudinally with respect to said board so as to be brought into alignment with any of the tracks 14 on center board 11.

The rear portion of the center board includes on each side a lateral shoulder 32 which is disposed between the two sets of rollers 33. Because of said shoulders the board at its rear portion is too wide to permit full withdrawal of the center board out of the cabinet. The rollers, obviously, permit easy movement of the center board into and out of the cabinet.

Now I shall describe the manner in which the cabinet and the slide panels may be used. Nor-

normally the center board is fully contained within the cabinet, with the side boards 21 and 23 folded under said center board, as shown in Figs. 7 and 8. When the center board is in this position, only the first panel may be seen in the open front of the cabinet. Now, assuming that other panels are to be displayed for inspection, the center board is pulled out far enough to permit the side boards to be swung up from the hinges to a horizontal position. In order to accomplish this, supporting finger 31 at the front is swung outwardly from under side board 23, permitting both side boards to drop down from the hinges. Each side board may now be raised manually to the level of the center board and retained in this position by means of the respective arms 25 which are swung from their pivotal positions under the center board to stand laterally under the side boards. Assuming now that a selected panel 18 is to be displayed, track 28, supported on T-blocks 30, is shifted longitudinally with respect to its side board until said track is aligned with a selected track 14 containing the selected panel, as shown in Fig. 3. The panel may now be slid laterally from its track 14 to said track 28, whereupon said track may be moved forwardly on said blocks 31 till it is aligned with the front panel. The same operation is followed with respect to a panel which is to be displayed on the opposite side board. Here, also, the panel selected from the center board is first shifted laterally into track 28 and then with the track moved forwardly in slots 27 till it is aligned with the front panel. Thus three panels may be displayed side by side, as best shown in Fig. 4. The panels on the side board may be returned to their place by reversing the procedure, that is, by sliding the track 28 back into alignment with the track on the center board from which the respective panel has been removed, whereupon said panel may be shifted back into its original position on the center board. In order to slide the center board back into the cabinet, the side boards are folded under said center board and the latter is pushed back into the cabinet.

It will be understood that some changes may be made in the construction of my device, but that this may be accomplished without departing from the inventive principle disclosed herein.

What I therefore wish to claim is as follows:

1. A display device for merchandise, as described, said device comprising a cabinet having an open front, a center board slidably disposed therein for withdrawal through said open front, a plurality of parallel tracks mounted transversely on the center board, a hinged side board on each side of the center board, a single track transversely mounted on each side board, the track being slideably mounted thereon for movement longitudinally with respect to said side board and being adapted to be brought into alignment with any track on the center board, a plurality of upright panels slidably seated in the tracks on the center board, each panel being adapted to be shifted laterally into the track on either side board.

2. A merchandise display device of the kind described, comprising a cabinet having an open front, a horizontal center board adapted for partial withdrawal therefrom, a plurality of parallel tracks disposed transversely on the center board in a spaced relation to each other, a side board hinged to each side of the center board, means to align the side boards at the level of the center board, each side board being provided with

two slots spaced from each other and disposed parallel to the center board, a sliding block in each slot, a single track mounted on said blocks and disposed transversely to the length of the center board, the track being adapted to be moved with said blocks for alignment with a selected track upon the center board, a plurality of upright panels slideably disposed in tracks on the center board, each of them being adapted to be shifted laterally into a track on either side board.

3. A device of the kind described, the device comprising a cabinet having an open front, a horizontal board slideably disposed therein and adapted to be pulled out outwardly through the open front, a side board hinged to each side of the center board and adapted to be raised to the level of the center board, pivoted arm means on the under side of the center board to sustain the side boards at the level of the center board,

20 a plurality of transverse tracks on the center board, each side board being provided with two slots spaced from each other and running parallel to the center board, a sliding block in each slot, a single track mounted on said blocks transversely to the slots and adapted to be aligned with a selected track on the center board, a vertical merchandise display panel disposed in each track on the center board, each of the panels being adapted to be slidably moved out of its track

30 into the single track on either side board.

4. A device of the kind described, said device including a horizontal board and two side boards hinged thereto, a plurality of transverse tracks on the center board and a single transverse track on each side board, means to support the side boards at the level of the center board, the single track being movable longitudinally on each side board for alignment with any track on the center board, a plurality of display panels in the tracks

40 on the center board, each panel being adapted to be shifted laterally into the single track on the side board.

5. A device of the kind described, the device comprising a cabinet having an open front, a horizontal board slideably disposed therein and adapted to be pulled out outwardly through the open front, a side board hinged to each side of the center board, said side boards being normally in a folded position under the center board,

50 parallel thereto, but being adapted to be raised to the level of the center board, pivoted arm means on the under side of the center board to sustain the side boards at the level of the center board, a plurality of transverse tracks on the center board, each side board being provided with two slots spaced from each other and running parallel to the center board, a sliding block in each slot, a single track mounted on said blocks transversely to the slots and adapted to be aligned with a selected track on the center board, a vertical merchandise display panel disposed in each track on the center board, each of the panels being adapted to be slidably moved out of its track

60 into the single track on either side board.

WALTER SCHNEWIND.
